UNITED STATES PATENT OFFICE

EDUARD SCHIEGRIES, OF DUISBURG-MEIDERICH, GERMANY

TAMPING MACHINE

Application filed January 29, 1931, Serial No. 512,226, and in Germany February 5, 1930.

This invention relates to tamping machines and has for its object to prevent the tamping material from being forced back by the molten iron, or fluid pressure, and by the back suction of the plunger of the machine itself.

According to the invention this object is attained in an extremely simple manner by the arrangement of a closing valve situated between the advanced position of the plunger and the mouth-piece of the machine. The closing valve is operated by a compressed air motor which also operates the plunger of the machine; the plunger motor is provided with a piston which slides in a compressed air cylinder, the movement of the closing valve being regulated by air compressed by the said piston. The closing valve automatically closes on the back stroke of the piston and opens when the piston advances providing sufficient counter pressure exists in the motor.

The accompanying drawings illustrate, by way of example, one construction of the invention, Figures 1, 2 and 3 being sectional elevations of the tamping machine in various working positions, and Fig. 4 is an enlarged sectional view of the cylinder, showing the valve control.

In these drawings 1 is the tamping machine in which a piston 12 carrying a plunger 2 is advanced and retarded by compressed air supplied to the cylinder 10, when the piston 12 advances it causes the plunger 2 to push stopping material through the mouth-piece 4 into the tap hole to be stopped, the stopping material first being fed into the machine through the funnel 3. Between the position of the forward stroke of the plunger 2 and the mouth-piece 4 is arranged a closing valve 5, for closing the said mouth-piece 4, which is connected to a piston 6 which slides in a compressed air cylinder 7, the said closing valve 5 being opened and closed by means of air pressure conveyed from the cylinder 10 of the plunger motor to the compressed air cylinder 7 of the valve motor by means of pipe lines 8 and 9.

By turning the control lever 13 the eccentric three-port slide valve 14 is moved either to the left or to the right so that either the right cylinder side communicates through the chan-

nel 16 or the left cylinder side through the channel 15 with the compressed air container connected to the nipple 18. In the first case, the left cylinder side and in the second case the right cylinder side communicates with the exhaust channel 17 leading into the open air. On each cylinder side is provided a pressure piston valve 11 or 11' which may occupy two positions. It is obvious from Fig. 4 that by the pressure exerted on the cylinder side, the piston of the valve is lifted against a spring so that the compressed air pipe 8 or 9 communicates with the cylinder. If the superatmospheric pressure on the cylinder side is eliminated, the valve occupies the position shown in Fig. 4 on the left and in this position the compressed air pipe 8 communicates with the outer air.

As is obvious from Figure 1, filling material is first introduced through the funnel 3. Since when the plunger 2 is withdrawn superatmospheric pressure prevails on the right side of the cylinder 10, the piston 6 and with it the valve 5 is lowered. If the lever 13 is reversed, the right side of the cylinder 10 will be emptied and the left side filled with superatmospheric pressure so that the piston 12 with the plunger 2 will be moved forward and at the same time the piston 6 with the valve 5 will be moved upward as shown in Fig. 2. If the control lever 13 is again reversed, the valve 5 will again be closed (as is shown in Figures 3 and 4) and the piston 12 will again be returned to its normal position whereupon the operation may be repeated.

It will be clearly understood from the foregoing that in an arrangement according to the present invention no molten metal can flow back from the furnace into the tamping machine, and also the arrangement is extremely simple in construction and is safe and can be easily operated.

What I claim and desire to secure by Letters Patent is:—

1. A tamping machine comprising a tamping plunger, a compressed air motor operating the plunger, means for admitting compressed air to the motor, a mouth-piece through which stopping material is delivered by the plunger, a closing valve for the said

mouth-piece, a compressed air motor for operating the said closing valve, and means whereby the compressed air motor for operating the closing valve is operated by counter pressure in the plunger motor at each end of the stroke of the plunger piston.

2. A tamping machine comprising a tamping plunger, a compressed air motor operating the plunger, means for admitting compressed air to the motor, a mouth-piece through which stopping material is delivered by the plunger, a closing valve for the said mouth-piece, a compressed air motor for operating the said closing valve, pipe lines connecting the rear end of the plunger motor to the underside of the valve motor and the forward end of the plunger motor to the top of the valve motor and means whereby the compressed air motor for operating the closing valve is operated through the pipe lines by counter pressure in the plunger motor at each end of the stroke of the plunger piston.

3. A tamping machine comprising a tamping plunger, a compressed air motor operating the plunger, means for admitting compressed air to the motor, a mouth-piece through which stopping material is delivered by the plunger, a closing valve for the said mouth-piece, a compressed air motor for operating the said closing valve, pipe lines connecting the rear end of the plunger motor to the underside of the valve motor and the forward end of the plunger motor to the top of the valve motor, automatic spring controlled air valves provided in the said pipe lines, the said valves being arranged to open only to admit compressed air to the valve motor when the piston of the plunger motor is at each end of its stroke.

4. A tamping machine comprising a tamping plunger, a compressed air motor operating the plunger, means for admitting compressed air to the motor, a mouth-piece through which stopping material is delivered by the plunger, a closing valve for the said mouth-piece, a compressed air motor for operating the said closing valve, pipe lines connecting the rear end of the plunger motor to the underside of the valve motor and the forward end of the plunger motor to the top of the valve motor, automatic spring controlled air valves provided in the said pipe lines, the said valves being arranged to open only to admit compressed air to the valve motor when the piston of the plunger motor has compressed air in the ends of the motor cylinder sufficient to overcome the load of the springs in the air valves.
